LLOYD COLE AND SAMUEL A. MORRIS, OF PAWHUSKA, OKLAHOMA.

GUIDE-COOLING SYSTEM.

Application filed September 4, 1925. Serial No. 54,520.

In locomotives and similar devices, the cross heads connected to the piston rods of the engine cylinders reciprocating on the guide rails cause the said rails to become 5 intensely heated and also to burn babbitt out of gibbs and to create knocking which is very objectionable. When the locomotive travels ahead the greatest amount of friction, and consequently heat, is applied by 10 the cross head to the upper rail, and when the locomotive is reversed the lower guide rail is subjected to friction and heat. It may, therefore, be considered the primary 15 object of this invention to maintain the guide rails for the cross heads of locomotives or the like in a comparatively cool condition, by the introduction of a continuous flow of a cooling agent therethrough.

It is a further object of the invention to 20 provide a means for introducing a cooling agent through conduits in the guide rails for the cross heads of an engine which is actuated by the reciprocation of the said cross head.

To the attainment of the foregoing the invention consists in the improvement as hereinafter described and definitely claimed.

In the drawings:—

Figure 1 is a side elevation illustrating the application of our improvement.

Figure 2 is a top plan view thereof with parts broken away.

Figure 3 is a sectional view on the line 3—3 of Figure 1.

Figure 4 is a sectional view on the line 4—4 of Figure 1.

Figure 5 is a sectional view on the line 5—5 of Figure 4.

Figure 6 is a side elevation showing the manner in which the cooling fluid may be taken directly from the engine tender.

Figure 7 is an elevation to illustrate the manner in which the fluid may be influenced 45 by air pressure.

Figure 8 is a sectional view through the air nozzle casing.

While in the drawings we have illustrated the improvement only in connection with the upper guide rail of the cross head it is obvious that the same may be likewise applied to the lower guide rail. However, as the locomotive mostly travels ahead, the importance of over-heating of the upper guide rail will be appreciated. Also in the certain figures of the drawings we have illus-

trated the fluid conducting means arranged on the upper guide rail.

Referring now to the drawings in detail, and to Figures 1 to 5 in particular, the numeral 1 designates a cylinder, of a locomotive. The cylinder has arranged therein the usual piston, reciprocated in the usual manner. The rod for the piston is indicated by the numeral 2 and this rod is adjustably secured on a boss that projects from the inner edge of a cross head 3. The cross head has pivotally secured thereto the usual connecting rod 4. The upper and lower edges of the cross heads have secured thereon shoes, 5 commonly termed gibbs. These shoes are centrally grooved for the reception of the upper and lower guide rails 6 and 7, respectively, which project from and are usually formed with the cylinder 1.

Mounted on the upper guide rails 1, there is a pump 7. The pump may be constructed in any desired manner and has both its inlet and outlet conduits provided with valves, whereby the sucker rod or piston in the pump will, upon its strokes, draw a cooling fluid thereinto and eject the said fluid therefrom. The outlet pipe for the fluid is indicated by the numeral 8. This pipe is directed toward the cylinder 1 and is disposed above the guide rail 6. The pipe has a downwardly extending branch 9 connected with a conduit 10 which communicates with a transversely arranged chamber 11 in the guide rail 6. The chamber has communicating therewith longitudinally arranged conduits 12 formed in the said guide rail, and these conduits communicate with a second chamber, similar to the chamber 11, in the guide rail. The last mentioned chamber is provided with a conduit similar to the conduit 10 to which is connected a pipe 13. The pipe 13 has an angle branch connected to and communicating with the top of a supply tank or radiator 14, and the outlet pipe between the tank 14 and the pump 7 is indicated by the numeral 15. The rod for the sucker or piston of the pump 7 is indicated by the numeral 16. This rod has its outer end formed with laterally extending arms 17, respectively, and these arms pass through elongated slots 18 formed in the outer ends of levers 19. Each lever 19 is pivoted, as at 20, to the sides of the rail 6, and each lever has its lower end received between spaced pins 21 on the sides of the cross head 3. Of course, the supply tank for the cooling fluid

is provided with a normally closed inlet opening. The fluid may be water or any other liquid cooling agent. The reciprocation of the cross head 3 will swing the lever 19, causing the rod 16 for the sucker or piston in the pump, to be reciprocated. Thus the pump will draw fluid from the tank 14 and force the said fluid through the pipes 8 and 9 into the chamber 11, and from thence through the conduits 12, returning the said fluid through the pipe 13 to the tank 14. In this manner it will be noted that a continuous flow of fluid is maintained as long as the locomotive is in operation. The fluid, when reentering the tank 14 will become cool, and for this reason we have stated that the said tank is in the nature of a radiator. The continuous flow of fluid through the rail 6 will prevent the over-heating of the said rail.

In Figure 6 the guide rail is constructed as previously described, but the means for introducing a cooling fluid therethrough is different. In this figure a portion of a locomotive is indicated by the numeral 50, the tender therefor by the numeral 51, From the water compartment in the tender 51 there leads a pipe 52 that is directed to a turbine 53, and from thence to the fluid inlet for the rail 54. The turbine is actuated by steam pressure from the boiler of the locomotive. The return pipe from the rail 54 to the top of the water compartment, is indicated by the numeral 55, and the over-flow pipe for the turbine by the numeral 56.

In Figure 7 of the drawings a water containing tank is indicated by the numeral 57, the pipe leading therefrom to the inlet for the upper rail 58 is indicated by the numeral 59. The outlet fluid pipe is indicated by the numeral 60. In this pipe there is a coupling 61 having an angle branch 62 that receives therein a nozzle 63 connected with a pipe 64 that leads to a source of air under pressure. The passage through the pipe 64 is controlled by a valve 65 and screwed in the coupling 61 there is a pipe 67 that communicates with the top of the tank 57. The pressure of air of course causes the water to continuously circulate between the tank 57 and the rail 58, while the steam actuated turbine 53 imparts a like continuous circulation of water between the rail 54 and the water compartment in the tender 51.

We have disclosed several methods by which the water or like cooling fluid is circulated through the rail but we do not wish

to be restricted to the precise features of construction herein disclosed and hold ourselves entitled to make such changes therefrom as fairly fall within the scope of what we claim. 60

Having described the invention, we claim:—

1. The combination with a locomotive 65 having guide rails for the cross head which is reciprocated by the piston rod of said locomotive, said rails having longitudinal conduits, and means for forcing a cooling fluid through said conduits. 70

2. The combination with a locomotive 75 having guide rails for the cross head which is reciprocated by the piston rod of said locomotive, said rails having longitudinal conduits, and means actuated by the reciprocation of the cross head for forcing a cooling fluid through said conduits. 75

3. Guide rails for the cross head of a locomotive or the like, said rails having longitudinal conduits extending a determined distance therethrough and merging into transversely arranged chambers in the said rails, pipe members connected with the chambers, a tank containing a cooling fluid to which one of said pipe members is connected, a pump having a pipe connection with the tank and to which the second of the first mentioned pipe members is connected, valves controlling the inlet and outlet ports in the pump, a plunger in the pump having a rod 80 90 extending through one end thereof, said rod having lateral extensions on the outer end thereof, levers pivotally secured to the sides of the guide rails having slots through which the lateral extensions of the plunger 85 95 rod pass and spaced elements on the sides of the cross head contacting with the opposite edges of the levers for swinging the said levers to reciprocate the plunger in the pump when the cross head is operated. 100

4. The combination with a locomotive 105 having guide rails for the cross head which is reciprocated by the piston rod of the locomotive, said rails having longitudinal conduits having widened passages at the ends thereof, and means for forcibly injecting a cooling fluid into one of the passages to cause the said fluid to continuously circulate through the conduits and between both of the passages. 110

In testimony whereof we affix our signatures.

LLOYD COLE.
SAMUEL A. MORRIS.
